UNITED STATES PATENT OFFICE.

WILLIAM H. THOMAS, OF CLEVELAND, OHIO.

DISPLAY-CRATE.

No. 828,441.

Specification of Letters Patent.

Patented Aug. 14, 1906.

Application filed April 1, 1905. Serial No. 253,241.

To all whom it may concern:

Be it known that I, WILLIAM H. THOMAS, a citizen of the United States, and a resident of Cleveland, county of Cuyahoga, and State 5 of Ohio, have invented a new and useful Improvement in Display-Crates, of which the following is a specification, the principle of the invention being herein explained and the best mode in which I have contemplated applying that principle, so as to distinguish it 10 from other inventions.

My invention relates to display-crates, and particularly to devices of this character which are utilized for retaining fruit in such 15 a manner as will keep it fresh for the longest possible period and also display it advantageously.

Said invention consists of means herein-after fully described, and specifically set forth 20 in the claims.

The annexed drawings and the following description set forth in detail certain means embodying the invention, such disclosed means constituting but one of various 25 mechanical forms in which the principle of the invention may be used.

In said annexed drawings, Figure 1 represents a perspective view of my improved display-crate, the cover being lifted up and partially broken away. Fig. 2 represents a central longitudinal section taken upon the plane indicated by the line 2 2, Fig. 3. Fig. 3 represents an end view; and Fig. 4 represents a transverse section taken upon the plane indicated by the line 4 4, Fig. 2, the body of the 35 crate, however, being tilted forward from the position shown in said Fig. 2.

My improved crate comprises, essentially, a receptacle or case A for the fruit or other 40 articles to be kept and displayed, means for retaining such articles fresh for the longest possible period, and standards B for supporting the receptacle A, and in which standards said receptacle is adapted to be tilted into 45 any desired position within certain limits, so as to advantageously display the fruit. Suitable side and end members a and a', respectively, are provided for the receptacle, secured together in any approved manner and 50 further held together by a lower strengthening member a². Suitably hinged to a side member a is the transparent cover a³ of any approved construction. There is no bottom proper to my improved crate; but a series of 55 transverse slats a⁴, supported at their ends upon the member a² and disconnected later-

ally from each other, form, in effect, a base for supporting the articles contained in the crate. The side and end members a and a', respectively, are provided with slots or perforations a⁵, any suitable number desired, and over said perforations a⁵ and above the slats a⁴ is secured a suitable reticulated material a⁶, such as wire screen, wire gauze, netting, &c. The above-described construction 60 of receptacle provides efficient means for holding the fruit, guarding same from insects, dirt, &c., and also secures a thorough circulation of air, which latter condition I have found to materially increase the period of 65 time during which the fruit may be kept fresh.

For supporting the receptacle A, I have provided two lateral standards B, preferably iron castings, which also serve as handles for 70 the crate. Each standard comprises a base portion b and an arched portion b', as clearly seen in Figs. 1 and 3. In the arched portion b', I provide a plurality of longitudinal grooves b², three, as shown, and adapted to engage 75 with and play in these grooves are pins b³, secured to the receptacle A. Such grooves, in effect, provide curved bearing-surfaces on which the pins b³ slidably rest. I have made the two pins that engage the two lower 80 grooves somewhat smaller than the third or upper pin, have secured them to the strengthening member a², and also provided them with suitable heads b⁴, so that they will not become detached from the grooves b². The 85 upper pin is secured in the end member a' of the receptacle A and is provided at its outer end with a thumb-screw b⁵. It will be noted that by loosening the thumb-screw b⁵ this 90 construction enables the crate to be tilted 95 forwardly, as in Fig. 4, or to lie horizontally, as in Fig. 3, or in any intermediate position, as desired, the crate being secured in such position by screwing up the thumb-screw so that it binds upon the arched member b' of 100 the standard B.

Having described my invention in detail, that which I particularly point out and distinctly claim is—

1. In a display-crate, the combination of 105 two standards each comprising a base portion and an arched portion supported upon said base portion and having a plurality of longitudinal grooves; a receptacle provided with a plurality of pins attached to its ends 110 and adapted to play in said grooves, respectively, whereby the inclination of the recep-

tacle is rendered adjustable; and thumb-screws for securing said pins in said grooves in any desired position.

2. In a display-crate, the combination of
5 two standards each comprising a base portion and an arched portion supported thereon and having grooves described upon arcs of the same circle; a receptacle provided with a plurality of pins attached to its ends and
10 adapted to play in said grooves, respectively, whereby the inclination of the receptacle is rendered adjustable; and thumb-screws adapted to secure said pins in said grooves in any desired position.

- 15 3. In a display-crate, the combination of two standards each comprising a base por-

tion and an arched portion supported thereon and having a plurality of longitudinal grooves; a receptacle provided with perforations in its bottom and sides, and bearing a ²⁰ plurality of pins on each end adapted to play in the grooves of the corresponding standard, whereby the inclination of said receptacle is rendered adjustable; reticulated material covering the perforations in said receptacle; and ²⁵ thumb-screws adapted to secure said pins in said grooves in any desired position.

Signed by me this 30th day of March, 1905.

WILLIAM H. THOMAS.
